[57] CLAIM

The ornamental design for electrical adapter, substantially as shown and described.

DESCRIPTION

FIG. 1 is a perspective view of an electrical adapter showing our new design;

FIG. 2 is an end view thereof on a reduced scale;

FIG. 3 is a top view thereof on a reduced scale;

FIG. 4 is a view of the end opposite that shown in FIG.

2 on a reduced scale;

FIG. 5 is a side view thereof on a reduced scale.

*Fig. 5.**Fig. 3.**Fig. 4.*
